UNITED STATES PATENT OFFICE

156,464

CIGARETTE SNUFFER

John R. Robbins, Alleghany, Calif.

Application August 6, 1949, Serial No. 4,332

Term of patent 14 years

(Cl. D85—2)

To all whom it may concern:

Be it known that I, John R. Robbins, a citizen of the United States of America, residing at Alleghany, in the county of Sierra and State of California, have invented a new, original, and ornamental Design for a Cigarette Snuffer, of which the following is a specification, reference being made to the accompanying drawings, forming a part thereof.

Fig. 1 is a top-plan view of a cigarette snuffer, showing my new design.

Fig. 2 is a side elevational view thereof, and

Fig. 3 is an end elevational view.

I claim:

The ornamental design for a cigarette snuffer, substantially as shown.

JOHN R. ROBBINS.
